ABSTRACT OF THE DISCLOSURE

A unitary slip and drag block structure including a 15 tubular member having longitudinally spaced slip and drag portions, said member having slots extending longitudinally for less than the full length of said member to divide said slip and drag portions into a plurality of interconnected segments which are expansible and contractible jointly as well as independently on each other. 20

This is a division of application Ser. No. 500,946, filed Oct. 22, 1965. 25

This invention relates to a well tool and, more particularly, to a packer apparatus for use in a well bore.

In the drilling and production of oil wells, it is often necessary to isolate zones or formations in the well bore in order to produce from and to permit or prevent the treating of such selected zones. The isolation of such zones or formations is commonly done by use of packers or bridge plugs. The present invention is primarily concerned with a tubing-type retrieval packer for use in a cased well bore. Such packers normally include a slip and drag block assembly in combination with a packer element. The packer is set by first unlocking a jaying mechanism and then applying tension or compression to the running in tubing which sequentially sets the slips into the well casing and expands the packer element. The expanded packer element seals off an annulus between the casing and the body of the packer. At some later time, the packer may be retrieved by manipulating the tubing to sequentially contract the packer element and unlock the slips from the casing. The packer is then locked in an inactive position by the jaying mechanism and retrieved to the surface. 40

In the event the packer should become stuck, a shearing device is usually provided between the packer body and the assembly holding the packer element. By applying greater than normal forces to the tubing string, the stuck parts can be made to shear from the body so that the body portion of the packer may be retrieved. The remainder of the tool is then fished or drilled out. 50

In the construction of such packers, it is important to maintain the apparatus as simple as possible for the reason that the more complicated the mechanism may be, the more likelihood there is that the mechanism will malfunction and prevent the retrieval of the packer by normal means.

It has been found that springs used for operating the slips and drag blocks are particularly susceptible to corrosive action of well fluids and often fail to operate. The failure of the springs to operate may cause the packer to become stuck in the well. Non-corrosive springs on the other hand are expensive and further add to the cost of the packer. In a typical packer, the slip and drag block assembly may be comprised of six slips, six slip pins, six drag blocks and eighteen springs; each being separate parts. Cost and susceptibility to malfunction are normally proportional to the number of individual parts comprising the assemblies. Where such packers are left in the well

2

bore for use over extended periods of time, the cost of manufacture of the packer becomes even more important. It is, therefore, an object of the present invention to provide a new and improved packer which is economical to construct and simple in its operation. 5

With this and other objects in view, the present invention relates to a packer having a resilient element expandable by virtue of relative movement between upper and lower gauge rings. An expander cone associated with one of the gauge rings actuates slips to provide a rigid stop for that gauge ring against which movement of the other gauge ring compresses the resilient element and thereby laterally expands the element into engagement with the well. Slip and drag block means are constructed as a single unit. The drag block means permits a jaying mechanism to be operated, which, in turn, provides for relative movement between the slips and expander cone. Shear means are provided between one of the gauge rings maintaining the packer element expanded and the packer mandrel so that should the apparatus become stuck in the well bore, the shear ring may be sheared to let the packer element collapse and permit removal of the tool from the well. The shear ring is so constructed as to permit a convenient selection of shearing forces. 20

A complete understanding of this invention may be had by reference to the following detailed description when read in conjunction with the accompanying drawings illustrating an embodiment thereof, wherein:

FIG. 1 shows a partial sectional view of a packer embodying features of the present invention;

FIG. 2 shows a partial sectional view of a packer utilizing an alternative slip and drag block arrangement;

FIG. 3 shows a sectional view of part of a packer, illustrating a shearing mechanism;

FIG. 4 is a sectional view taken along lines 6—6 of FIG. 3; and

FIG. 5 is a side view of the shearing device shown in FIGS. 3 and 4.

Referring to FIG. 1, the packer apparatus is comprised of a mandrel or body 12 which is threaded at its upper end for connection to a string of tubing. An elastomer packer 14 element is positioned about the body and is supported on one end by an upper gauge ring 16 which, in turn, is connected to the mandrel by a shear pin or shear ring 18. The other end of the packer element is supported by a combination gauge ring and expander 20. The gauge ring and expander 20 is supported on the mandrel by means of an annular shoulder 22 extending outwardly from the mandrel. 45

A unitary member 24 is arranged about the packer mandrel below the expander. This unitary member has portions thereon serving as slips and drag blocks. The member is preferably machined or otherwise formed of a single piece of material. An upper portion 26 of this unitary member has teeth 28 formed therein to render the upper portion operable as slips. The upper end of the slip portion 26 has an inwardly sloping surface 30 thereon which mates with an outwardly sloping surface 32 formed on the expander 20. These sloping surfaces 30 are arranged so that relative movement of the slip and expander toward one another will cause the slip to cam outwardly into engagement with the well casing. An enlarged portion 34 at the other end of the unitary member forms a drag block means for frictionally engaging the interior of the well casing. A plurality of longitudinal slots 36 are formed through the unitary member with adjacent slots running from alternate ends of the member to a terminal point 38 near the opposite end. The terminal point is in the shape of a hole through the member which serves as a stress relief means. This arrangement of slots in the unitary member permits the member

to be compressed and thus reduced in size or diameter upon the application of radial forces inwardly against the member. A space 40 is provided between the unitary member and the mandrel to permit such radial compression. The lower end of the unitary member is supported by a drag block cage 42 having a hook-shaped annular lug 44 extending upwardly therefrom. The hook portion 46 on the lug is received within a recess 48 at the lower end of the unitary member. An inwardly extending J pin 50 which is attached to the drag block cage 42 is slidably received within a conventional J-slot 52 normally used with such packer devices.

In the operation of the apparatus shown in FIG. 1, the packer is lowered into the well bore to a depth where it is desired to expand the packer against the wall of the well. At this point, the packer mandrel is raised upwardly and rotated to place the J-pin 50 into a long longitudinal section of the J-slot 52. The mandrel is then lowered with the pin 50 riding upwardly in the long section of the J-slot. The J-pin 50 is held from downward movement with the mandrel by frictional engagement of the drag block 34 against the wall of the well. Relative movement between the mandrel and unitary member, on which the drag block is formed, causes the sloping portion 30 of the slip to ride upwardly on the surface 32 of the expander thereby camming the slips outwardly into gripping engagement with the well bore. Further downward movement of the mandrel pushes the upper gauge ring, packer element, and lower gauge ring expander against the now-anchored slips and compresses the elastomer packing element between the upper and lower gauge rings. Such compression of the ends of the packer element causes the element to expand radially outwardly into sealing engagement with the wall of the well.

When it is desired to unset the packer, weight is picked up off the mandrel 12 by lifting on the tubing string. This permits the packer element to contract and lets the expander cone slide upwardly from behind the slip thereby permitting the slip to disengage from the wall of the well. The teeth 48 on the slips are slanted downwardly to facilitate their disengagement from the wall of the well when pulled upwardly. Should the packer fail to unset, a larger than normal force may be applied upwardly on the mandrel which force is sufficient to shear the pin 18 connecting the upper gauge ring to the mandrel. Shearing of this pin releases the upper gauge ring to permit decompression of the elastomer packing element thus releasing the sealing engagement.

The apparatus has thus far been described as being operated as a compression set packer. However, it is readily seen that by inverting the apparatus on the tubing string, the packer may be set by applying tension forces to the mandrel.

Referring now to FIG. 2 of the drawings, an alternative arrangement of parts is shown which features a separate slip and drag block. The drag block 54 is constructed from a unitary piece of material and has the same slotted arrangement as shown with respect to the unitary member in FIG. 1. A drag block cage 56 is slidably received about the mandrel 12, the cage having overlapping flange members 58 which engage end tabs 59 on the drag block to support the drag block on the packer. A J-pin 60 which is connected to the cage 56 extends inwardly therefrom and is movably received within J-slot 62 in the mandrel 12. A hook-shaped annular lug 64 extends upwardly from the cage and is received in a complementary recess 66 on a slip member 68. One end of slip member 68 has a sloping portion 70 thereon which cooperates with oppositely sloping portion 72 on the expander cone 74 positioned below the packer element 76.

In the operation of the apparatus shown in FIG. 2, the packer is run into the well bore to a point at which it is desired to expand the packer. The mandrel is raised upwardly and rotated to move the J-pin 60 into an elongated portion of the J-slot 62 whereupon the mandrel is

lowered. Lowering of the mandrel at this point causes the expander cone 74 to move downwardly beneath the slips 68. The slips are prevented from moving downwardly due to the frictional engagement of the drag block 54 against the well bore. This downward movement of the expander cone 74 cams the slips 68 outwardly into gripping engagement with the well bore to anchor the slips therein. Continued downward movement compresses the packer element between the upper and lower gauge rings and radially expands the packer element 76 outwardly into sealing engagement with the well bore. The packer of FIG. 2 is unset in a manner similar to that set forth with respect to the operation of the apparatus of FIG. 1.

FIGS. 3, 4 and 5 show a shearing means to be used with a well tool such as the packer described herein. Referring to FIG. 3, the upper end of a packer mandrel 78 is shown attached to the lower end of a tubing 80. A packer element 82 is shown positioned about the mandrel. An upper gauging 84 is positioned over the end of the packer element. An annular recess 86 is formed in the outer wall of the packer mandrel. An arcuate shaped shear member 88 is positioned about the mandrel with the inner edge of the shear member fitted into the recess 86 on the mandrel. A plurality of openings in the shear member receive screws 90 for fastening the shear member to the gauge ring 84. Radial slots or grooves 92 (FIG. 4, 5) are formed part way through the shear member 88 so that portions or segments of the shear member may be easily broken therefrom. Each of the portions between the recesses 92 in the shear member has an opening for receiving a screw or bolt 90 to fasten each segment of the member to the gauge ring 84.

With the arrangement of shearing means as set forth above, the amount of shear means needed in a well tool may be determined and selected at the well location. The tool is shipped to the well location with a maximum amount of arcuate segments or shear means which would be needed in any situation. The operator then removes segments of the arcuate member until the number of the segments remaining corresponds to the shear value he wishes to provide on the tool. Each of the segments represents an equal amount of shear resistive material, for each segment may require 10,000 pounds force to shear the segment. The grooves 92 in the arcuate shear member are sufficiently deep to permit the pieces to be easily broken from the ring. As will be appreciated, the shear members would be placed about the mandrel in such a way as to balance or distribute the shearing forces applied about the mandrel.

Although the features of the invention herein have been described for use with a packer, it is readily seen that such features would have application to other well tools. Additionally, while particular embodiments of the present invention have been shown and described, it is apparent that changes and modifications may be made without departing from this invention in its broader aspects and, therefore, the aim in the appended claims is to cover all such changes and modifications as fall within the true spirit and scope of this invention.

What is claimed is:

1. A tool adapted for use in a well comprising: an elongated body, a unitary annular sleeve on said body, said sleeve having a drag block portion for frictionally engaging the wall of a well and a slip portion for gripping the wall of a well, said drag block portion and slip portion being longitudinally spaced on said unitary annular sleeve by a connecting portion having a relatively thin cross section, said sleeve having a plurality of adjacent slots formed in the wall of said sleeve, said adjacent slots running from alternate ends of said sleeve to stress relief means near the opposite end of said sleeve, expander means for moving said slip portion into gripping engagement with the well, and selectively operable means for effecting relative movement between said expander means

and slip portion to operate said slip portion, said connecting portion of said unitary annular sleeve permitting radial movement of said slip portion relative to said drag block portion.

2. A unitary slip and drag block structure for use in anchoring a well tool in a well bore, comprising an elongated generally tubular member having a slip portion adjacent one end with teeth formed on its outer periphery, said slip portion having inclined inner surfaces, said member having a drag portion adjacent its other end with outer peripheral surfaces adapted to frictionally engage a well conduit wall, said member further having slots extending in longitudinal directions for less than the full length of said member to divide said slip and drag portions into a plurality of circumferentially spaced segments which are joined to an adjacent segment at each end whereby said slip and drag portions are jointly as well as independently expandable and contractible.

3. The structure of claim 2 wherein said member further has a thin-walled portion between said slip and drag portions.

4. A unitary slip and drag block structure for use in anchoring a well tool in a well bore, comprising: an elongated generally tubular member having a first portion

with teeth formed on its outer periphery, said first portion having inclined inner surfaces, said member having a second portion spaced from said first portion and having outer peripheral surfaces adapted to frictionally engage a well conduit wall, said member having slots extending in alternating longitudinal directions from one end of said member to points adjacent the opposite end thereof, and said member providing resilient portions interconnecting opposite ends of said segments with adjacent segments, so that said first and second portions are jointly as well as independently expandable and contractible.
